(57) **CLAIM**

The ornamental design for a kids alarm clock, as shown and described.

DESCRIPTION

FIG. 1 is a perspective view of a kids alarm clock showing my new design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side view; and,

FIG. 7 is a bottom plan view thereof.

The broken lines in the drawings illustrate portions of the kids alarm clock that form no part of the claimed design.
